COMBINATION LOCK

Abraham Lewit and Pablo Wrba, Buenos Aires,
Argentina

Application April 24, 1939, Serial No. 269,604

2 Claims. (Cl. 70—301)

The present invention relates to a combination lock, and more particularly to a lock wherein the combination can be changed at will.

The object of the invention therefore resides in the provision of a combination lock simple in character, efficient in use, cheap of manufacture and the combination of which can be selectively changed by means of adjustments outside of said lock.

As an example, and for purposes of illustration, an embodiment of the invention is shown in the annexed drawings, wherein:

Figure 1 is a plan view of a top disc,
Figure 1a is an elevation of the above,
Figure 2 is a plan view of a free disc,
Figure 2a is an elevation of the above,
Figure 3 is a plan view of an actuating disc,
Figure 3a is an elevation of the above,
Figure 4 is a plan view of a fixed separator disc,

Figure 4a is an elevation of the above,
Figure 5 is a plan view of a base disc,
Figure 5a is an elevation of the above,
Figure 6 is a plan view of a translator disc,
Figure 6a is an elevation of the above,
Figure 7 is a plan view of a spring washer,
Figure 7a is an elevation of the above,
Figure 8 is a plan view of the partly-assembled lock showing the bolt,

Figure 9 is an elevation of the above,
Figure 10 is a plan view of stacked discs shown in Figs. 1, 2, 3, 5,

Figure 10a is an elevation of the above,
Figure 11 shows a bottom view of control disc,
Figure 12 is a side view of the above, assembled on operating shaft,

Figure 13 is a simplified side elevational view of the lock assembled, and

Figure 14 is a similar view showing the arrangement of the bolt actuating means.

Referring to the drawings, numerals 1—3—5—6—7 and 8 represent flat discs of substantially the same diameter and all of which have a circular central aperture 2 for mounting on a hollow shaft.

The top disc 1 is provided with a depending tongue 1a and is notched marginally to form the radial steps 1b and 1c.

The loose disc 3 is circular with the exception of notch 4 provided at the margin thereof.

The disc 5 is irregularly formed and comprises a portion 5g of larger radius defined by the steps 5d and 5f. A triangular tongue 5a is punched in the periphery of said portion 5g adjacent the step 5f. The remaining portion of the periphery is

cut also to provide a wide notch limited by the radial steps 5c and 5b. Finally, a small notch 5e is formed between step 5d and the adjoining margin of smaller radius.

5 The above discs 1—3—5 form together a set of movable members, one of such sets being provided for each cipher of the lock combination.

Between each of the disc sets above mentioned, a fixed separator disc 6 is provided which includes a conical notch 14 and a pair of thin short projections 6a—6d defining therebetween the space 6b.

The base disc 7 includes a tapered notch 24 similar to that of disc 6 and for the same purpose to be described later. An extension of larger radius 7a forms the steps 7b—7c, with bent lug 7d immediately adjacent the step 7c forming one of a group of three lugs 7d equidistantly disposed around the periphery of the disc. A semi-circular depression 7e is provided near step 7b.

The translator disc 8 differs principally from the others in that an outwardly diverging finger 8d is formed on the margin thereof and angularly directed downwardly. A lug 8c is punched near

25 the edge of the disc, adjacent the inner junction of the finger with the disc, said lug being bent sharply at right angles and extending downwardly from the body of the disc. A second finger 8b, shorter than the first, is also formed in the outer portion of the disc but bent upwardly and concentrically with the periphery of the disc. This finger is cut short at its free end to provide a notch 8e having on the adjacent edge of the body an up-turned projection 8f and a pointed tooth 8a.

30 The lock is assembled in a casing 10 having parallel walls 10k and 10g, in the last of which an aperture 10f is provided for the bolt 11. This bolt embodies an extension 11b slotted at 11d for a retaining screw 12 threadedly secured to the bottom of casing 10.

35 A tooth 11c is provided on 11b for bolt driving purposes. On the bottom of casing 10 there is also mounted vertically a hollow shaft 10a having an upper notch 10b, as shown in Figure 8.

40 As illustrated in Fig. 9, the shaft 10a serves to centre properly the various discs described previously. The casing bottom further includes the spacer posts 10j, a bolt-pressing spring 10h pivoted at 10i, a stop post 10e for securing the fixed discs and limiting the rotary movement of the moving discs, and a roller 10d mounted on a flat spring 10s for pressing against the disc 13. Finally, the bolt 11 includes the upwardly projected lug 11a.

The casing is completed by a cover 15 secured to the posts 10j and through which the operating shaft 13b of operating knob 13c is adapted to project.

The operating disc 13 is notched at 13a to contact with spring-pressed roller 10d to produce audible clicks. Thus, the lock may be operated without referring visually to the numerals printed on the cover 15.

To the shaft 13b, inside the casing, there is attached the operating disc 13 comprising the downwardly depending studs 13d to which is pivoted at 14a an arcuate arch 14 embodying the cross-pieces 14b—14c and the tapered lug 14d.

A flat spring 13e (Fig. 12) is used to project said arch 14 away from disc 13.

Assembly

In the casing 10, having the sides 10g and 10k, the bolt 11 is assembled and the first disc to be placed therein is base disc 7 which is inserted over the shaft 10a, said disc having the lugs 7d directed downwardly to form a space between 7 and 10.

Thereover, the actuating disc 5 is disposed with tooth 5a upwardly with the step 5f adjacent the stop 10e, as shown in Figure 8. Thereover, the free disc 3 is disposed with the groove 4 corresponding to the similar groove 24 of disc 7 opposite the extending member 11a. Thereafter, the top disc 1 is inserted with the lug 1a disposed in groove 5e of disc 5 so as to turn therewith.

The fixed or separator disc 6 is finally disposed over the set of three discs above-mentioned with the teeth 6a and 6b straddling the stop 10e so as to lock said separator in registration with its groove 14 in front of member 11a of the bolt 11.

As disclosed before, a set of the three discs 1—5—3 is used for each cipher of a combination, together with a fixed separator disc in order to insulate or separate the other sets from each other. On top of the stack of sets of discs, the disc 8 is disposed with lug 8c and finger 8d directed downwardly, so as to engage 8c with step 5d of disc 5.

Then the shaft 13b is assembled, as shown in Figure 13, so as to engage one of the grooves 13a with the roller 10d, the arch 14 of disc 13 being disposed in such a manner that projection 14b engages the finger 8d of disc 8. In order to dispose the lid or cover 15 in position, the knob 13c is taken off the shaft 13b, whereupon the cover is placed in position and the knob again secured to its shaft 13b by means of set screw 13f.

When the lock is assembled as above indicated, the bolt can be retracted inside the casing, that is, with the lug 11a inside the aligned notches 4, 14 and 24, of the superposed discs. To operate, the disc 13 is turned by means of handle 13c which, when contacting the second groove 13a with 10d, must at this time align tooth 14b with groove 8e allowing the passage of said tooth until it contacts the sector 5g of the disc 5, the turning of disc 13 being continued until the desired cipher is reached.

This operation is possible because at the time tooth 14b engages groove 8e it falls over the step

5f of disc 5 to move the tooth 5a thereof, whereby the arch 14 with the corresponding tooth 14b shall engage tooth 5a and move same a section of the cycle until the desired groove 13a is reached which corresponds to the cipher chosen. When this actuating disc 5 is turned, the disc 1 is operated therewith and the free disc 3 disposed between the two is frictionally rotated also.

The movement of discs 1—3—5 is obtained by means of tooth 8c of disc 8, the movement of this disc being made only when the arch 14 has taken a position under disc 7 and the casing 10 of the lock. When a complete turn of disc 13 is effectuated, tooth 14b is positioned at the extremity of finger 8d, remains thereover and slides upwardly until it reaches the shorter finger 8b to remain over the step 8f against the tooth 8a until a new cycle of the lock which has remained closed.

To open the lock, it is necessary to turn disc 13 until roller 10d is in the desired groove 13a and when returning to said groove the bolt will be free for opening of the lock. In these conditions, the tooth 14b engages the tooth 11c of the arm 11b of the bolt, whereby turning the handle 13c shall produce displacement of said bolt within the casing.

Upon releasing the handle 13c, the spring 10h will be effective to push upwardly the arm 11b to force the bolt 11 through aperture 10f, the lock being operable as a single lock by the turning of handle 13c.

To close the lock, it will be sufficient to give the handle a few turns until disc 3, changing the position of aperture 4, prevents retraction of the bolt until all members have been disposed as previously disclosed.

It is to be understood that the form of our invention herein shown and described is to be taken as a preferred example of the same, and that various changes as to the shape, size and arrangement of parts may be resorted to without departing from the spirit of our invention or the scope of the subjoined claims.

Having thus described our invention, we claim:

1. A combination lock of the character described, comprising a set of three movable discs for each cipher of a lock combination, a separator disc for each of said sets, a spring bolt, means on the middle disc for allowing passage of the bolt, means for releasing said bolt, an arcuate pivoted member for revolving the discs of each set according to the combination, and a translator disc for moving vertically the arcuate member from one set to another.

2. In a combination lock, a series of disc sets, each of said set corresponding to a cipher of a combination, spacing means between said sets to prevent relative movement therebetween, a spring-pressed bolt, means on one disc of each set for preventing movement of the bolt, an operating knob for rotating a disc-turning arcuate member, and a translator disc for consecutively displacing the arcuate member from one set to another.
